UNITED STATES PATENT OFFICE

ROBERT V. STONER, OF MUNCIE, INDIANA

DESIGN FOR A BATHROOM CABINET STOOL

Application filed November 28, 1930. Serial No. 37,819. Term of patent 3½ years.

To all whom it may concern:

Be it known, that I, ROBERT V. STONER, a citizen of the United States, residing at Muncie, in the county of Delaware and State of Indiana, have invented a new original, and ornamental Design for a Bathroom Cabinet Stool, of which the following is a specification, reference being had to the accompanying drawing, forming part thereof.

The figure is a perspective view of a bathroom cabinet stool showing my new design.

I claim:

The ornamental design for a bath-room cabinet stool as shown.

In witness whereof I, ROBERT V. STONER, have hereunto set my hand at Muncie, Indiana, this 20th day of November, A. D., one thousand nine hundred and thirty.

ROBERT V. STONER.
